UNITED STATES PATENT OFFICE.

SAMUEL T. McCLAREN, OF ST. PETERSBURG, FLORIDA.

CASEMENT-WINDOW-OPERATING DEVICE.

Specification of Letters Patent. Patented Apr. 18, 1916.

1,179,640.

Application filed December 13, 1915. Serial No. 66,550.

To all whom it may concern:

Be it known that I, SAMUEL T. MCCLAREN, a citizen of the United States, residing at St. Petersburg, in the county of Pinellas and State of Florida, have invented certain new and useful Improvements in Casement-Window-Operating Devices; and I do declare the following to be a full, clear, and exact description of the invention, such as will enable others skilled in the art to which it appertains to make and use the same.

This invention relates to improvements in operating devices for casement windows, shutters and like.

The main object of the invention is to so construct a device of this character that considerable leverage will be exerted thereby on the initial opening movement thereof and at the end of its closing movement, whereby the member to which it is applied may be easily and promptly opened and tightly closed on the actuation of said device.

Another object of the invention is to provide a simply constructed and efficient device of this character which operates automatically on the swinging of the member to which it is applied to lock said member and hold it until manually released.

Another object is to provide a device of this character which may be applied equally well to a sash hinged either to the sides or to the top or bottom of a window frame and which may be used in connection with screened windows and mounted to work either right or left handed as desired.

With the above and other objects in view, the invention consists of certain novel features of construction, combination and arrangement of parts as will be more fully described and claimed.

In the accompanying drawings: Figure 1 represents a horizontal section through a window and frame showing this improved operating device applied and with the window in closed position; Fig. 2 is a similar view showing the window in open position; Fig. 3 is an enlarged detail vertical section; Fig. 4 is an enlarged detail horizontal section showing the locking means for the lever in operative position; Fig. 5 is a transverse section taken on the line 5—5 of Fig. 4; Fig. 6 is a similar view taken on the line 6—6 of Fig. 4.

In the embodiment illustrated, a casement

window 1 is shown hinged to the jamb 2 in the usual manner. A screen 3 is also shown mounted in the window frame in front of the outwardly opening window 1 and which is provided in the lower frame member 4 thereof with a slot 5 through which the sash actuating device constituting this invention is designed to pass and freely operate.

The operating device constituting this invention comprises a lever 10 which is here shown composed of a strip or bar of metal curved abruptly edgewise at one end to form an angularly disposed attaching arm 10^a. This lever is provided on its inner edge with a plurality of longitudinally spaced notches 11 for a purpose to be described. The free end of this lever arm 10^a is pivotally connected with a bracket 12 which is here shown L-shaped in cross section with one arm extending laterally and pivotally connected with the lever arm 10^a and the other arm secured to the inner face of the lower sash rail of the window 1 as is shown at 12, see Fig. 3. The free end of this lever 10 is preferably provided with an operating handle or knob 13 to provide for the ready grasping and operation of said lever. Secured to the window sill S in front of the screen 3 is a casing 14 which is open at its rear and closed throughout the remainder thereof, the open rear portion being disposed to register with the slot or opening 5 in the frame of the screen 3, see Figs. 3 and 4. This casing 14 may be of any suitable or desired shape and is shown as provided with a horizontally disposed partition 15 arranged between the top and bottom of said casing and which is designed to form a guard or guide for the operating lever 10 which passes through the opening 5 in the screen and through an opening 16 in one side wall of the casing, 14, see Figs. 1, 2, 3 and 4.

Extending transversely through the casing 14 and guard 15 mounted therein and entering the window sill S, are two spaced longitudinally alining screws 17 and 18 between which said lever is mounted and in connection with which it is designed to cooperate in performing its function as will be hereinafter more fully described. The screw 17 is so positioned that the notches 11 of the lever 10 are adapted to be engaged therewith and these notches are forced into

engagement with said screw by a spring 19 which is coiled around the screw 18 above the guard or partition 15 with one arm 20 thereof positioned to engage the rear face 5 or side of the screw 17 and with the other arm extending forwardly and provided with a downturned finger 21 which is arranged to bear on the edge of the lever 10 opposite to that in which the notches 11 10 are formed. It will thus be observed that this spring 19 exerts its tension to normally force said lever into engagement with the screw 17 so that when said lever is moved longitudinally with its inner edge slidably 15 engaging said screw, it will automatically spring into locking engagement with the screw immediately when one of the notches 11 thereof comes opposite said screw and when so positioned, the arm 20 together 20 with the finger 21 on the arm 22 will yieldably but reliably hold said lever in locked engagement with the screw 17.

A roller 23 is revolvably mounted on the screw 18 below the guard or partition 15, 25 see Figs. 4, 5 and 6. This roller 23 is designed to engage the curved rear edge of the lever arm 10^a, the angle of which is such that when said lever is pressed against the roller 23 at the beginning of the opening 30 or at the end of the closing movement of the lever, said roller operates as a fulcrum for said lever whereby considerable leverage is produced and the sash easily and quickly forced open or closed according to the direction in which the lever 10 is moved. 35 This leverage is obtained owing to the peculiar angle of the lever arm or end 10^a formed by the abrupt curve at its junction with the body of the lever and its engagement with the roller 23.

From the above description, taken in connection with the accompanying drawings, 40 it will be obvious that this lever 10 is straight throughout the greater portion of its length, the curve therein being formed 45 at the junction thereof with its arm 10^a and said curve being so abrupt as to position said arm in a plane substantially at right angles to the body portion of the lever.

The lever arm 10^a is here shown provided 50 at its pivoted end with a plurality of longitudinally spaced apertures 10' to provide for the proper setting of the sash in or out from the face of the frame and this is accomplished by using the aperture 10' most suitable for connecting the lever 10 with the bracket 12 and then cutting off the portion of the lever which projects beyond the 55 aperture 10' which has been used.

A catch 24 is mounted on the window sill S and is designed to engage and securely lock the lever 10 when the sash is in closed position as shown in Figs. 1 and 3, whereby 60 the sash is firmly held closed. This catch 24 is here shown in the form of a metal

plate or strap with an upturned hook or nose 25 for engaging and holding the lever 10.

In the operation of this improved device when the window is in closed position as 70 shown in Fig. 1 and it is desired to open it, the knob 13 is grasped by the operator and the lever moved laterally outward against the tension of the spring 19 which causes 75 the rear edge of said lever to come in contact with the roller 23 and this engagement, together with the force exerted by the operator on the handle 13, will forcibly push the sash 1 into open position as shown in Fig. 2 and when it has been disposed at the desired 80 angle, one of the notches 11 of said lever will be engaged with the screw 17 and the spring 19 bearing on said lever and screw will reliably hold the lever in locked engagement with the screw, thereby firmly and 85 reliably holding the sash in adjusted position where it will remain until the lever 10 is manually released from the screw 17.

From the foregoing description, it will 90 also be obvious that should the window be left open without engaging one of the notches of the lever 10 with the screw 17 and should the sash 1 swing either outwardly or inwardly under the pressure of wind or otherwise, it would be immediately 95 locked when the first notch in said lever comes opposite the screw 17 and thus all possibility of the sash being blown back and forth and broken is prevented.

It will thus be seen that this device may 100 be applied to a window without marring or injuring the frame of either the sash or the window as two screws only are necessary for connecting the device with the window sash and three for connecting it with the sill. 105

I claim as my invention:

1. The combination with a casement window, of an operating device therefor comprising a lever provided in one edge with a plurality of longitudinally spaced notches, spaced uprights positioned for the passage of said lever between them, a spring coiled on one of said uprights and having arms, one of which is positioned to engage said lever and the other to engage the other upright, whereby said lever is yieldably held in contact with one of said uprights. 115

2. The combination with a casement window, of an operating device therefor comprising a lever provided in one edge with a plurality of longitudinally spaced notches, a casing having spaced upright elements mounted therein, said casing having openings in its oppositely disposed side walls for the passage of said lever therethrough, said lever being arranged between said upright elements, a spring coiled on one of said elements and having arms, one positioned to engage said lever and the other to engage the other upright element whereby said le- 125

ver is yieldably held in contact with one of said upright elements.

3. The combination with a casement window, of an operating device therefor comprising a curved lever provided in one edge with a plurality of longitudinally spaced notches, a casing having spaced upright elements mounted therein, said casing having openings in its oppositely disposed side walls for the passage of said lever therethrough, said lever being arranged between 20 said upright elements, a spring coiled on one of said elements and having arms, one positioned to engage said lever and the other to engage the other upright element, whereby said lever is yieldably held in contact with one of said upright elements, and a roller mounted on said spring carried upright element and adapted to engage the edge of said lever opposite to that which carries the notches.

4. The combination with a casement window, of an operating device therefor comprising a curved lever provided in one edge with a plurality of longitudinally spaced

notches, a casing having spaced upright elements mounted therein, said casing having openings in its oppositely disposed side walls for the passage of said lever therethrough, said lever being arranged between 20 said upright elements, a spring coiled on one of said elements and having arms, one positioned to engage said lever and the other to engage the other upright element, whereby said lever is yieldably held in contact with one of said upright elements, a roller mounted on said spring carried upright element and adapted to engage the edge of said lever opposite to that which carries the notches, and a horizontally disposed partition mounted in said casing intermediately between its top and bottom walls and over said lever forming a guard for the lever.

In testimony whereof I have hereunto set my hand in presence of two subscribing witnesses.

SAMUEL T. McCLAREN.
